SHOE

Arthur Bender, New York, N. Y.

Application March 28, 1932, Serial No. 601,704,
and in Canada March 17, 1932. Renewed July
18, 1933

1 Claim. (Cl. 12—142)

This invention relates to shoes and to a method of constructing the rear portion thereof.

One important object of the invention is to provide an improved and novel construction for the rear portions of shoes whereby the unsightly rear seam will be eliminated.

A second important object of the invention is to provide a novel construction of shoe wherein a single cover sheet is used to cover the counters 10 and heel so that no seams appear on the exterior, either at the rear of the counter or between the counter and heel proper.

A third important object of the invention is to provide a novel method of constructing the 15 rear portion of a shoe whereby the heel body will be held firmly to the upper by an outer or covering sheet.

With the above and other objects in view, the invention consists in general of certain novel 20 details of construction and a method of manufacture hereinafter fully described, illustrated in the accompanying drawing and specifically claimed.

In the accompanying drawing like characters 25 of reference indicate like parts in the several views, and:—

Figure 1 is a side elevation of a shoe constructed in accordance with this invention.

Figure 2 is a rear elevation thereof.

Figure 3 is a section on the line 3—3 of Figure 1.

Figure 4 is a section on the line 4—4 of Figure 30 1, the view being of the partly constructed shoe 1, the view being of the partly constructed shoe and showing the counter molded over the bottom of the rear portion of the last.

Figure 5 is a section on the line 5—5 of Figure 1.

Figure 6 is a plan view of the cover sheet.

In the embodiment of the invention as herein disclosed there is shown the rear portion of an ordinary last 10 and, in Figure 4, the counter 11 is shown as under-lapping this last and secured 40 thereto by the usual lasting nails or brads 12.

After the counter has been properly molded to the last an incision 13, of horse-shoe shape, is made around this under-lapping portion so as to free the portions 14 forming the bottom edge portion of the finished counter. This bottom edge

45 portion is turned down into alignment with the sides of the counter and thus provide a seat for the upper end of a heel body or core 15 which is fitted against the under side of the last in such 50 position that its upper portion has its sides and rear surrounded by the lower portions 14 of the counter.

After the heel body has been properly positioned the cover sheet is applied. This cover sheet is shown before its application in Figure 6

where it will be seen to consist of a unitary sheet of some suitable material such as a fabric or thin leather which is formed with two lateral portions substantially symmetrical about a vertical median line indicated at 16. The upper middle portion of this sheet is of generally rectangular shape and from each side of this upper middle portion extends a wing, the upper middle portion being shown at 17 and the wings at 18. The portions 17 and 18 are wrapped around the outsides of the back and side portions of the counter. Below the middle portion 17 is a heel portion 19 which, when applied, covers the sides and rear of the heel body. The lower edges of the wings 18 are provided with relief notches to aid 65 in folding over the cover sheet. The cover sheet, when applied, covers the counter and heel body in a smooth and unbroken manner and the finished shoe shows no rear seam nor any joint or seam between the upper and the heel, this being 70 clearly shown in Figures 1 and 2. Finally a finishing strip 21 is applied over the front of the heel body and under the arch of the shoe to cover the exposed edges of the cover sheet at these 75 places. The upper and forward edges of the 80 cover sheet are preferably finished with a suitable binding 22.

What is claimed, is:—

That method of constructing the heel portion 85 of a shoe which consists in providing a last, molding a shoe counter to the last to provide under-lapping portions, cutting a horse-shoe shaped incision around the under-lapped bottom portion of the counter to leave a free edge at the bottom of the counter, seating the upper end of a 90 heel body against the last within the free edge of the counter to cause said free edge to enclose the sides and rear of the upper end of the heel body, and covering the exterior of the counter and heel body with a single piece of covering 95 material.

ARTHUR BENDER.
